(57) **CLAIM**

The ornamental design for an exercise device with treadles, as shown and described.

DESCRIPTION

FIG. 1 is an isometric view of an exercise device with treadles, in accordance with the present invention;
FIG. 2 is a front elevation view thereof;
FIG. 3 is a rear elevation view thereof;
FIG. 4 is a left side elevation view thereof;
FIG. 5 is a right side elevation view thereof; and,
FIG. 6 is a top plan view thereof.

The bottom of the exercise device with treadles is not shown and forms no part of the claimed design.

UNITED STATES PATENT AND TRADEMARK OFFICE
CERTIFICATE OF CORRECTION

PATENT NO. : Des. 527,060 S
APPLICATION NO. : 29/201898
DATED : August 22, 2006
INVENTOR(S) : Edward L. Flick et al.

Page 1 of 1

It is certified that error appears in the above-identified patent and that said Letters Patent is hereby corrected as shown below:

Title page, Item (56), Page 4, line 61, References Cited, U.S. Patent Documents, insert the following:

2004/0018918 A1	01/2004	Reyes et al.
2004/0132583 A1	07/2004	Ohrt et al.

Signed and Sealed this

Thirteenth Day of March, 2007

A handwritten signature in black ink, appearing to read "Jon W. Dudas". The signature is written in a cursive style with a large, stylized "J" and "W".

JON W. DUDAS
Director of the United States Patent and Trademark Office
